UNITED STATES PATENT OFFICE.

MARTIN SCHRENKEISEN, OF NEW YORK, N. Y.

IMPROVEMENT IN ROCKING-CHAIRS.

Specification forming part of Letters Patent No. 177,754, dated May 23, 1876; application filed February 21, 1876.

To all whom it may concern:

Be it known that I, MARTIN SCHRENKEISEN, of the city, county, and State of New York, have invented a new and useful Improvement in Rocking-Chairs, of which the following is a specification:

The figure is a vertical section of a rocking-chair to which my improvement has been applied.

The object of this invention is to improve the construction of the rocking-chair for which Letters Patent No. 156,127 were issued to Charles Brada, October 20, 1874, to counteract the tendency of said chair to lean forward, and thus make it more convenient and comfortable in use.

The invention consists in the combination of the second or rear set of springs with the forward set of springs, the arms, the chair, and the pedestal, as hereinafter fully described.

A represents the body of the chair, the lower edges of the side frames of which are rounded off like rockers, and rest and rock upon the upper edges of the side frames of the pedestal B. To the inner side of the upper part of the side frames of the pedestal B are attached arms C, which project upward, and have outwardly-projecting pins formed upon their upper ends, which enter V-slots in the iron plates D, attached to the inner sides of the lower parts or rockers of the chair A.

To studs formed upon the inner sides of the lower parts of the arms C are attached the ends of coiled springs E, the other ends of which project forward, and are connected with

the forward part of the chair-body A by pins or links.

As thus far described, the parts are all found in Letters Patent No. 156,127, and about their construction there is nothing new.

To the studs of the arms C are attached the ends of a second set of springs, F, which are coiled in the opposite direction from the springs E, and their other ends project to the rearward, and are connected with the rear parts of the chair A, as shown in the figure. By this construction the springs F resist the tendency of the chair A to be drawn forward by the springs E, and keep it in proper position. The springs E F are made of such a strength as not to interfere with the easy movement of the chair when in use.

This invention is intended as an improvement upon the above-cited patent, which belongs to me.

In the chairs made under the Brada patent, the spring draws them forward, so that the seat loses its true position, while the pedestal slips. These objections are entirely remedied by the counterbalance-springs which I have placed in the rear; hence,

What I claim is—

The rear springs F, arranged on a chair to counterbalance the front springs E, the two sets of springs being coiled in opposite directions, as shown and described.

MARTIN SCHRENKEISEN.
